REAR PANEL UNIT FOR A VEHICLE

Jesse R. Birchard, Walled Lake, Mich., Albert D. Mortrude, Pompano Beach, Fla., and Ray C. Conner, Battle Creek, Mich., assignors to Clark Equipment Company, a corporation of Delaware

Filed Sept. 20, 1968, Ser. No. 13,644

Term of patent 14 years

Int. Cl. D12—10

U.S. Cl. D14—3

FIG. 1

FIG. 2

FIG. 3

FIG. 4

FIG. 5

FIG. 6

FIG. 7

FIGURE 1 is a right rear quarter perspective view of the rear panel unit for a vehicle, showing our new design; FIGURE 2 is a rear elevational view thereof;

FIGURE 3 is a rear elevational view of a modified form thereof;

FIGURES 4 and 5 are right and left side elevational views, respectively, of the rear panel unit shown in FIGURE 2; and

FIGURES 6 and 7 are right and left side elevational views, respectively, of the rear panel unit shown in FIG. 3.

The portion in broken lines is shown for illustrative purposes only.

We claim:

The ornamental design for a rear panel unit for a vehicle, as shown and described.
